(57) **CLAIM**

The ornamental design for a horizontal magazine belt clip, as shown and described.

DESCRIPTION

FIG. 1 is a front perspective view of the horizontal magazine belt clip;

FIG. 2 is a rear perspective view of the horizontal magazine belt clip;

FIG. 3 is a front elevational view of the horizontal magazine belt clip;

FIG. 4 is a back elevational view of the horizontal magazine belt clip;

FIG. 5 is a right side elevational view of the horizontal magazine belt clip;

FIG. 6 is a left side elevational view of the horizontal magazine belt clip;

FIG. 7 is a top plan view of the horizontal magazine belt clip;

FIG. 8 is a bottom plan view of the horizontal magazine belt clip; and,

FIG. 9 is a front elevational view of the horizontal magazine belt clip, shown in a state of use.

The dash-dash broken lines in FIG. 9 depict environmental subject matter that form no part of the claimed design.

1 Claim, 7 Drawing Sheets
